UNITED STATES PATENT OFFICE.

OTTO KRAUS, OF NEW YORK, N. Y., ASSIGNOR TO KRAUS ENGINE COMPANY, OF NEW YORK, N. Y., A CORPORATION OF NEW YORK.

APPARATUS FOR THE PRODUCTION OF WORKING FLUIDS.

1,227,275.

Specification of Letters Patent.

Patented May 22, 1917.

Application filed November 17, 1915. Serial No. 61,933.

To all whom it may concern:

Be it known that I, OTTO KRAUS, a citizen of the United States of America, residing at the borough of Manhattan, in the city, county, and State of New York, have invented certain new and useful Improvements in Apparatus for the Production and Utilization of Working Fluids, of which the following is a specification, reference being had to the accompanying drawings.

This invention relates to improvements in apparatus for the production and utilization of working fluids and particularly to improvements in apparatus for the generation of a mixture of steam and the products of combustion of liquid fuel and in an apparatus for the utilization of that mixture as a working fluid; and an object of this invention is to provide a generating apparatus which will be simple in construction, comparatively cheap in manufacture and installation, and durable and efficient in operation and use. A further object of this invention is to provide a well balanced motor adapted for the utilization of the working fluid furnished by this generating apparatus.

In the drawings illustrating the principle of this invention and the best mode now known to me of applying that principle, Figure 1 is a central longitudinal vertical section through the generating apparatus; Fig. 2 is a section on the line 2—2 of Fig. 1; Fig. 3 illustrates a modified form of the flue in the steam-generating chamber; Fig. 4 is an elevation of the motor and the generating apparatus assembled; Fig. 5 is a section on the line 5—5 of Fig. 4; Fig. 6 is a section on the line 6—6 of Fig. 4; and Fig. 7 is a sectional view of a modified form of a working cylinder.

The compressed air is led from an air-compressor A, through the pipe a, to the chamber b, which is connected by the piping c with the air space d above the liquid fuel (as a hydrocarbon oil) contained in the fuel-tank e. The latter is connected, by the piping f, with the inlet-passage g leading to the liquid-fuel reservoir h, in which there is mounted a recessed float i carried by an arm j pivotally fastened, as at k, to the side wall of the reservoir h. The arm j carries a needle-valve m, the free end of which controls the inner end

of the fuel-inlet passage g. An air passage b', hollow post n and opening n' connect the chamber b with the annular chamber n'' that surrounds the atomizer plug q; and this chamber n'' communicates, through the opening n*, hollow post n* and hole h', with the air-space h'' above the liquid fuel in the reservoir h. Air under pressure flows, from the chamber b through the passage b', hollow post n, and aperture n', to the annular chamber n'' and thence, through the hole n*, hollow post n* and opening h', to the air-space h'', whereby the oil contained in the fuel-reservoir h is put under air pressure. An oil-feed pipe o extends downwardly from the top of the fuel-reservoir h to below the surface of the oil contained therein and leads the oil forced upwardly through the feed-pipe o to the passage p from which the oil flows into the chamber q', and thence through the atomizer-plug q, past the needle-valve r and through the nozzle s. By adjusting the needle-valve r, the amount of oil that is fed through the nozzle s may be controlled. The chamber b furthermore communicates with the valve-chamber t in the valve-casing u, in which there is mounted slidably a valve stem v carrying a valve w at its lower end and controlled by a coil-spring x wound around its upper end and arranged to hold the valve w against its seat. The spring x and the upper end of the valve-stem v are housed in a screw-cap y. The valve w controls the flow of compressed air from the valve-chamber t to the chamber z, from which the air flows under pressure to the combustion chamber 2. Air flows, under pressure, from the annular chamber n'', through the passage s', and atomizes or breaks up the oil flowing through the nozzle s so that this oil issues from the latter in the form of a fine spray. From the nozzle s, the oil is discharged into the combustion chamber 2 through a flaring or trumpet-shaped mouthpiece 3 formed with holes 4 through which air flows from the chamber z into the mouthpiece 3 and mingles with the oil-spray issuing from the nozzle s. The holes 4 are so arranged as to insure a proper mingling of the air with the atomized oil. Into the wall 5 of the combustion chamber 2, there is fitted an electric igniter 6, the sparks from which

serve to ignite the mixture of air and liquid fuel, which mixture then burns in the combustion chamber 2.

A water-pipe 7 leads from any suitable source of water supply, as a water-pump, to a passage 7' and thence to an annular chamber 8 surrounding the atomizer 9. The water fills this annular chamber 8 and thereby serves to water-jacket the atomizer 9 and to maintain the latter in a comparatively cool condition. From the annular chamber 8, the water flows through a water-passage 9 into a water-jacket 9' and thence through a water-passage 9" to a water-pipe 10 which extends downwardly through the vertically-disposed flue 11, the wall of which is formed with ports or outlet-openings 12. The mixture of burning gases and the products of combustion flow from the combustion chamber 2 through the opening 2', past the re-ignition device 6', and into the flue 11 and thence escape through the holes 12 formed in the wall thereof and through the outlet end 13 of the same, where the products of combustion meet the water which has flowed through the pipe 10 and collected in the bottom of the steam generator 14. The heated products of combustion, upon coming in contact with this water, breaks up and vaporizes the same; and the mixture of drops of water, vapor and the products of combustion flow upwardly through the steam-generating chamber 14 filled with chains 15 or the like that serve to sub-divide the currents of water, vapor, and products of combustion and to cause the intermingling thereof and to transfer heat from the products of combustion to the water and water vapor. The mixture finally escapes from the steam-generating chamber 14 through an opening 16' in its upper end and flows thence, through the conduit 16, to the valve-chambers 17 of the two-cylinder engine B.

Connected to the crank-shaft 19 of the motor B are the lower ends of the rods 20 the upper ends of which carry the pistons 21 that reciprocate slidingly in the cylinders 18. In the specific embodiment illustrated in the drawings, there are two power or working cylinders 18 and valve mechanisms therefor; but they are similar in construction and a description of one of them will suffice as a description of both. To the top of the valve-chest 22 there is fastened a bracket-arm 23 pivotally connected with one end of an arm 24, the other end of which is pivotally fastened to the upper end 25 of the valve-controlling rod 26 the lower end of which carries a cam-roller 27 that rests upon a cam 28 fastened to the cam-shaft 29 that is driven from the crank-shaft 19 by the intermeshing gears 19', 29'. Pivotally fastened to the arm 24 is the upper end of a valve-stem 30, the lower end of which carries an admission-valve 31. Mounted on the

upper end of this valve-stem 30 is a collar 32, between which and a bracket-arm 33 that extends laterally from the bracket 23, there is mounted a coil-spring 34 that tends to keep the inlet valve 31 seated. Fastened to the valve-controlling rod 26' is one end of the valve-lever 35 fulcrumed at 36 on a post 37 that rises from the valve-chest 22; and, to the other end of this valve-lever 35 there is pivotally fastened the upper end of a valve-stem 38 the lower end of which carries the exhaust-valve 39. Between the valve-lever 35 and the top of the valve-chest there is mounted an expansion coil-spring 40 which tends to hold the exhaust-valve 39 against its seat. The valve-controlling rod 26' is provided at its lower end with a roller 27' that bears against the cam 28' fast upon the cam-shaft 29. In the modified form shown in Fig. 7, no exhaust valve is provided and the working cylinder 18' is formed with exhaust ports 41 which permit the exhaust gases to escape to the exhaust-pipe 42. The admission-valve mechanism is substantially the same as that shown in Fig. 5. In Fig. 6, there is shown a section of the air-compressor cylinder 43, in which there reciprocates slidingly a piston 44 connected by the rod 45 with the crank-shaft 19. The spring-controlled air-admission valve is marked 46 and the air-outlet valve is designated by the numeral 47. The crank-shaft 19 is formed at one end with clutch-teeth 48 with which engage the teeth 49 on the end of a crank-arm 50 idly mounted on the reduced or stub end 51 projecting from the crank-shaft 19; and, at the other end of the latter, there is mounted a flywheel 52. It is to be observed that there is a nice balance between the thrust of the power pistons 20 and the resistance offered by the air-compressor pistons 45, so that smoothness of running, so desirable in automobile construction, is attained.

In Fig. 3, the flue 11' is in the form of an imperforate cylinder through which the products of combustion flow from end to end. A fusible safety-plug 14' is provided in the bottom of the steam-generating chamber 14. Should the supply of water fail, the heated products of combustion would melt the fusible part of the plug 14' and, by their escape, would draw attention to the condition then existing and, in time, would cause the engine to stop.

The apparatus may be started by the operator's grasping the crank-arm 50 and engaging the teeth 49 thereof with the teeth 48 formed on the end of the crank-shaft 19. By turning the latter, by means of the crank 50, in the direction indicated by the arrow in Fig. 4, the pistons 44 of the air-compressor A are caused to reciprocate and compressed air is forced past the outlet-valves 47 into the pipe a and chamber b, 130

whence a part of the air passes through the pipe *c* to the air-space *d* above the oil in the oil-tank *e*. Another part of the air flows, from the chamber *b*, through the air-passage *b'*, hollow post *n* and opening *n'* into the 5 annular chamber *n''* and thence, through the hole *n**, hollow post *n** and aperture *h'*, into the air-space *h''* above the oil in the oil-reservoir *h*, the pressure of the air in which forces the oil up through the oil- 10 feed pipe *o*, passage *p* and chamber *q'*, past the needle-valve *r* and out through the nozzle *s*. Air flowing from the annular chamber *n''* through the air-passage *s'* breaks the oil up into a fine spray which issues from 15 the nozzle *s* into the trumpet-shaped mouthpiece *3*, where it mingles with compressed air flowing from the chamber *b*, through the valve-chamber *t* and past the valve *w*, into the chamber *z* and thence through the holes 20 *4* into the mouthpiece *3*. Sparks from the electric igniter *6* set fire to the combustible mixture of air and oil-vapor, which mixture thereupon burns, the products of combustion flowing from the combustion-chamber *2* 25 through the opening *2'* and downwardly into the flue *11*, from which the products of combustion escape through the bottom thereof and through the ports *12*. The ignition device *6** quickly becomes incandescent and serves, by its wires *6**, to reignite the gaseous mixture in case the flame be extinguished. Water flows through the 30 annular water pipe *7* and passage *7'* into the water-jacket *8* and thence through the water-passage *9*, which leads to a water-jacket *9** that surrounds the combustion-chamber *2*. The water flows from the water-jacket *9** through an L-shaped passage *9** 35 into a water-pipe *10* that extends almost vertically downward through the flue *11*. Thus, the water is preheated in the water-jackets *8*, *9**, and in its travel through the passages *7'*, *9*, *9**, formed in the heated walls 40 of the combustion-chamber *2*. The products of combustion, passing through the water in the bottom of the steam-generating chamber *14*, vaporize this water; and the products of combustion escaping through the ports *12* 45 flow upwardly past the chains *15*. The mixture of the products of combustion, water and water-vapor flows upwardly past the chain-links *15*, which serve to break the currents up into fine streams and to cause the same to intermingle and to transfer heat from the products of combustion to the water and water-vapor, transforming the latter, at least in part, into super-heated steam. The mixture, constituting the working fluid, 50 finally enters the working cylinders *18* past the admission-valves *31*, when the same are opened by the rotation of the cam-shaft *29*. The pistons *21* are thereby forced downwardly, driving the crank-shaft *19*. Exhaust takes place, when the exhaust-valves 55

39 are opened and the exhaust gases flow outwardly through the exhaust-pipe *42*.

The following structural points deserve remark: By the provision of the water-jacket chamber *8* surrounding the fuel-atomizing device *q*, the fuel flowing therethrough is kept cool and does not become decomposed therein; and the regulation of the amount of fuel supplied is also simplified. The water preheated in the chamber *8* 70 flows through the passage *9* into the annular water-jacket chamber *9**, where it is further heated, and thence through the L-shaped passage *9**, from the wall of which it takes up more heat. Finally, the preheated water flows through the pipe *10* 80 wherein it absorbs still more heat from the burning gases and the highly-heated products of combustion flowing through the flue *11*. The water is, therefore, discharged 85 into the bottom of the steam-generator *14* in a highly-heated condition. The water-jacket *9** may, in an apparatus of small size, be dispensed with, in which case a passage will be provided connecting the passages *9*, *9**. The outer end of the passage *9* is closed by a screw-plug *9''*, by removing which the operator is enabled to force any suitable cleaner (not shown) through the passage *9* and water jacket *9**, and into 90 the passage *9**; and, when the plug *14** is removed, the cleaner may be forced through the pipe *10* and thence into the passage *9**; that is, the passages named may be cleaned 95 readily in the manner described. Similarly, 100 there is provided, in the front wall of the combustion chamber *2*, a passage *s** the outer end of which is closed by a screw-plug *s''* and the inner end of which communicates with the annular air-chamber *n''*. 105 This passage *s** is in direct line with the air-passage *s'*; therefore, by removing the screw-plug *s''*, the operator is enabled to force a suitable cleaner (as a wire) through the passages *s**, *s'*, and to remove the dirt 110 from these passages and the discharge or nozzle end *s* of the fuel-atomizing device *q*. By leading compressed air from the chamber *b* through the pipe *c* to the air-space *d* in the fuel-tank *e*, the oil therein is put under air pressure; and the oil in the oil-reservoir *h*, which is in communication with the fuel-tank *e*, is likewise placed under substantially an equal counter air-pressure 115 by the admission of compressed air from the chamber *b*, through the passage *b'*, post *n*, passage *n'*, annular air-chamber *n''*, post *n** and opening *h'*, to the air-space *h''* above the oil in the fuel-reservoir *h*. By means of the tapered valve *m* controlled by the 120 float *i*, the flow of oil from the fuel-tank *e* is regulated and the level of the oil in the fuel-reservoir *h* is kept substantially constant. It is to be noted that the upper end *p** of the oil-passage *p* discharges the oil 125 130

at the reduced part r^* of the shank of the needle-valve r . The spring-controlled valve w serves to reduce the pressure of the air flowing from the chamber b into the chamber z and thence into the combustion chamber 2; therefore, the air admitted to the combustion chamber 2 exerts a pressure lower than the pressure of the air acting, in the air-space h'' , upon the surface of the liquid fuel in the fuel-reservoir h ; hence, the oil forced upwardly from the latter and through the nozzle s into the combustion chamber 2 is impelled thereinto under pneumatic pressure higher than the gaseous pressure acting in the combustion chamber 2. Again, the pressure of the air in the annular air-chamber n'' and air-passage s' is higher than the pressure of the gases in the combustion chamber 2. It is to be observed that the compressed air acting upon the oil in the fuel-tank e and oil-reservoir h is derived from the same source (the chamber b) as the compressed air led to the combustion chamber 2 and the compressed air flowing through the air-passage s' and serving to atomize the oil and to assist in driving the same into the combustion chamber 2 against the gaseous pressure therein existing. The mouthpiece 3 serves to separate the spray issuing from the nozzle s into the combustion chamber 2 from the envelop of air which flows thereinto through the chamber z . By suitably positioning the perforations 4 in the mouthpiece 3, a proper commingling of the air and oil in the mouthpiece 3 is produced. Furthermore, the flaring character of the mouthpiece 3 insures that the air flowing through the chamber z into the combustion chamber 2 will be directed toward the wall of the latter and will therefore serve as a pneumatic envelop for the oil-spray core, as hereinbefore stated. Again, the discharge end of the trumpet-shaped mouthpiece throttles the air flowing past and outside of that end and causes some of the air to pass through the holes 4. The wall of the combustion chamber 2 converges or becomes funnel-shaped at 2^* so that the air and fuel become intimately mixed as they flow past the funnel-shaped portion 2^* of the combustion chamber 2 and pass through the opening 2^* . The reignition device 6^* is provided with refractory wires 6^* which become incandescent and serve, together with the body portion of the device, to reignite the gaseous mixture, should the flame become extinguished. Before complete combustion of all the oil occurs, the mixture is led downwardly through the flue 11, the area of the transverse section of which is less than the area of the transverse section of the combustion chamber 2. The steam-generator 14 surrounds the downwardly-extending flue 11, between which and the wall of the steam-

generator 14, the chain-links 15 are interposed and serve to subdivide into fine streams the products of combustion flowing through the openings 12 and the outlet end 13 formed in the flue 11 and to cause an intimate intermingling of the water and water-vapor with the products of combustion and a transfer of heat therefrom to the water and water vapor. The perforated discharge end of the flue 11 is tapered (Fig. 1) and the lower end of the steam-generator 14 is also reduced. Since the chain-links 15 surround the flue 11, heat radiating from the latter will be taken up by these chain-links and will, therefore, not be lost. If the water rises in the steam-generator 14, the products of combustion may nevertheless escape from the flue 11 quietly and without substantially greater resistance; for, the ports 12 permit the escape of the products of combustion otherwise than through the outlet end of the flue 11. The chain-links 15 near the level of the ports 12 will become highly heated by the burning gases and products of combustion flowing through the ports 12 and these chain-links 15 will later transfer the heat thus absorbed to the water and water-vapor flowing past them in finely divided streams. Moreover, by the provision of the ports 12, so much of the products of combustion is allowed to escape without having to pass through the water collected in the bottom of the generator 14 that the action of the latter is more quiet than it would otherwise be; that is, the disturbance of the water is not so great as in the case where all the products of combustion are made to pass through the water. Furthermore, in case the water should rise to an abnormal height, the escape of the products is facilitated by the provision of the ports 12. By removing the plug c^* from the T-coupling c^* in the pipe c , the operator is enabled to pass a cleaner downwardly through the passage b' and the passages in line therewith, for the purpose of cleaning the same of dirt and the like that may have accumulated therein.

The engine comprises an air-compressor A and a motor B, both of which act upon a common crank-shaft 19, the air-compressor rods 45 being connected to one end thereof and the motor-rods 20 being connected to its other end; that is, the air-compressor A lies wholly on one side of the vertical mid-line of the engine and the motor B wholly on the other side thereof. Whatever may be the number of compressor-cylinders 43, the number of power-cylinders 18 will be the same; and the combined number of compressor and power cylinders may be two, four, six, eight or any higher even number. Each compressor rod 45 is fastened to a pair of cranks 45* and each motor-rod 20 is fastened to a pair of cranks 20*. For each

crank-pair 45*, there is a crank-pair 20* in the same relative angular position therewith; and, for each compressor-piston 44, there is a motor-piston 21 in the same relative position of stroke therewith. By this arrangement of parts, a balance is obtained, which is a feature of this invention and novel in this type of engine. The working fluid may be used to drive a turbine 10 motor, to which may be direct-connected a rotary air-compressor; the generating part of the apparatus could remain the same in this case. That is, the pistons in the outside motor and compressor cylinders and the 15 cranks connected with said outside pistons are in the same position relative to each other, while the intermediate pistons and the cranks connected thereto are also in the same position relative to each other.

20 I claim:

1. An apparatus of the character described including a water-jacketed combustion chamber; and a water-jacketed fuel-atomizing device in communication therewith; the water-jacket about said device being separate from but in communication with the water-jacket around said combustion chamber and the water flowing from the first-named water-jacket to the last-named water-jacket.

2. An apparatus of the character described including a water-jacketed combustion chamber; and a water-jacketed fuel-atomizing device in communication therewith; the water-jacket about said device being in communication at its top with the

top of the water-jacket around said combustion chamber and the water flowing from the first-named water-jacket to the last-named water-jacket. 40

3. An apparatus of the character described including a horizontally-disposed combustion chamber; a steam generator the lower end of which extends downwardly from the outlet end of said chamber and is 45 in communication therewith; and means for leading water into said lower end.

4. An apparatus of the character described including a horizontally-disposed combustion chamber; a downwardly-extending 50 steam-generator; and chain-links in the latter.

5. An apparatus of the character described including a horizontally-disposed combustion chamber; a substantially vertically-disposed steam generator connected therewith; a flue which is mounted within said generator and is in communication with the outlet end of said combustion chamber, the outlet end of said flue lying near the 55 lower end of said steam generator; and means for leading the water to the latter.

Signed at the borough of Manhattan, city, county, and State of New York, this fifteenth day of November, A. D. 1915, in 60 65 the presence of the two undersigned witnesses.

OTTO KRAUS.

Witnesses:

JAMES HAMILTON,
M. E. WOARDELL.

Attest: OTTO KRAUS, Inventor, and JAMES HAMILTON, his attorney, New York, November 15, 1915.
